MINE ROOF SUPPORT

James M. Phillips, Pittsburgh, Pa., assignor to
 Phillips Mine and Mill Supply Company, Pitts-
 burgh, Pa., a corporation of Pennsylvania

Application November 17, 1945, Serial No. 629,236

7 Claims. (Cl. 61—45)

1

This invention relates to the supporting of roofs of mines and other underground workings, and is for a bracket for supporting timbering or cross beams under the roof of such a mine or underground working.

In the digging of mines and various types of subterranean tunnels, it is the practice, as the mine or tunnel is extended, to put cross timbers under the rock or earth formation which forms the roof of the tunnel. These cross timbers or roof supports are ordinarily held up against the roof of the mine by vertical posts at each side of the tunnel or mine entry. Since the roof supports are usually quite close together, this requires a considerable amount of timber. Also since the timber is of substantial dimensions it reduces the useful width of the tunnel or entry and requires added clearance for mine cars and mine locomotives.

The present invention has for its object to provide a bracket or support which may be anchored into the side walls of the mine entry or tunnel and provide a support for the cross beams under the roof.

My invention may be more fully understood by reference to the accompanying drawing, in which:

Fig. 1 is a perspective view representing the upper portion of the interior of the mine showing the support of my invention in place and holding up the cross timbers which support the roof:

Fig. 1 is a perspective view of a preferred embodiment of my invention:

Fig. 3 is a similar view of a modification;

Fig. 4 is a perspective view of still another modification, and showing also that the roof support in any event may be structural metal instead of timber; and

Fig. 5 is a transverse section through one of the supporting elements in the plane of line V—V of Fig. 4.

Referring first to Fig. 1, A designates one side wall of a tunnel or entry of a mine, B is the roof, and C are roof supports which may be either timbers or structural steel members. They extend across the full width of the tunnel or entry, bear against the roof, and are supported at each end by the supports constituting the present invention.

The supports as shown in Fig. 2 preferably comprise two long metal pins 2 having head portions 3 at the outer ends thereof. These pins are driven into holes drilled into the faces of the side walls. Supported on the projecting ends

2

of the pins 2 inwardly of the heads is a cross member or strap 4 which has a downwardly turned eye portion 5 at one end thereof through which one of the pins 2 is loosely passed. This forms a pivoted or hinged connection between the strap and one of the pins while the other end of the strap merely rests on the second pin.

The advantage of this arrangement is that the holes for the two pins are of course separately 10 drilled into the side wall of the mine. Because of the strap having an eye to pivot about one pin only, and merely resting on the other pin, any inequality in the spacing of the two pins can be accommodated and any inequality in the 15 height of the two pins can be accommodated. In other words, the holes drilled in the wall of the mine to receive the pin 2 need not be accurately spaced, and the strap 4 will be in position to hold the rough timber or beam notwithstanding this slight inequality. If the strap were 20 provided with two eyes similar to the eye 5 so that the two pins were held in fixed spaced relation, the holes for the pins would have to be very accurately positioned.

25 Also with this arrangement the pin which passes through the eye, together with the strap, can first be secured to the wall with the strap 4 hanging vertically downward. Then the timber can be put into place, the strap 4 swung up to 30 position under the timber, and the second pin may then be driven.

The strap 4 is preferably provided with some kind of abutments such as the upwardly extending lugs 6 properly spaced so that the timber which is supported thereon cannot slide up.

35 The device as described can be quickly installed in place, excessive time is not required in the positioning of the holes to receive the pins, the timbering can be put in place, the strap raised to position, and the second pin put in so that the timbering can press against the roof of the mine and does not have to be shifted about to get it in place. When it is in place, the eye 40 5 prevents the strap 4 from moving in the direction of its length off either of the pins. Therefore when the installation is made, it is safe, avoids supports up the side wall of the mine, and saves considerable expense.

45 The modification shown in Fig. 3 is quite similar to that shown in Fig. 2, except the support, instead of having a strap element made from rolled metal forged to shape, is in the form of a casting.

In Fig. 3 the pins as before are designated 2. 50 The support comprises an integral casting 7 hav-

ing downwardly directed lugs 8 at one end forming a groove or panel crosswise of the under member 7 to bear upon the right-hand pin 2. The member 7 merely rests on the left of the two pins. The casting is provided at each end with upstanding lugs 9 for holding the timber in place.

In this arrangement, as in Fig. 2, the support pivots on one pin and is loosely supported on the other. It can be used in the same manner as the form shown in Fig. 2, and the saddle-like engagement provided by the fitting of the lugs 8 astraddle one of the pins serves to keep the support from shifting in the direction of its length relative to the pins. At the same time the upstanding lugs 9 prevent the timbering of the cross pins from slipping off the support. The heads of the pins in this form, as in the form shown in Fig. 2, prevent the strap or support from moving outwardly from its position close to the face of the wall.

In the construction shown in Figs. 4 and 5, the two pins, designated 10, are of like construction, and is provided at its outer end with a half round projection 11 that is bent back over the shank of the pin for a short distance, providing a hook-like formation. A flat piece of metal 12 spans the distance between the two pins. It is engaged under the hooks 11. In this instance, as with the other two modifications, one pin may first be put into place, the cross beam or timber, shown in Fig. 4 as being an I-beam may then be raised into position, the support 12 then inserted under it, engaging under the hook of the pin which is first driven, and then the second pin is driven into place holding the roof supporting member or timber against the roof. The cross beam is restrained against shifting in the direction of the length of the strap 12 inasmuch as the hook portions 11 provide abutments in which the timber or cross beam would strike if it tended to move in one direction or the other transversely of its length. As shown in Fig. 5, the strap 12 is confined by the two rounded surfaces so that it can accommodate itself to slight irregularities in the heights of the two pins without binding.

All three embodiments of my invention provide a supporting bracket having two pins which are independent of each other with a supporting element carried by the projecting ends of the pins, restrained against movement outwardly from the plane of the wall by the pins. Each arrangement permits one pin and the support to first be put into place, after which the end of the timber can be put into position and the second pin driven. In all forms, provision is made to restrain the roof support once it is in place, from shifting in a direction transverse to its longitudinal axis.

While I have illustrated and described certain particular embodiments of my invention, it will be understood that this is merely by way of illustration, and that various modifications and changes may be made within the contemplation of my invention and under the scope of the following claims.

I claim:

1. A supporting assembly for roof supports of a mine or the like comprising a pair of separate pins adapted to be entered into one of the side walls of the mine, and a cross member mounted

on and spanning said pins and having one end pivotally movable relatively to one of them and on which one end portion of the roof support may be set, the other end of said cross member being straight and adapted to be rested on the other of said pins.

2. A supporting assembly for roof supports of a mine or the like comprising a pair of separate pins adapted to be entered into one of the side walls of the mine, and a cross member mounted on said pins and having one end pivotally movable relatively to one of them and on which one end portion of the roof support may rest, the other end of said cross member being freely movable with respect to and adapted to be rested upon the other of said pins, the pins having means at the outer ends thereof for preventing the cross member from slipping endwise off the pins.

20 3. A supporting assembly for the roof supports of a mine or the like comprising a pair of separate pins, a cross member supported on and spanning said pins and having means adjacent one end thereof embracing one of said pins for restraining the cross member against movement in the direction of its length relatively to said pin.

4. A supporting assembly for the roof supports of a mine or the like comprising a pair of separate pins, a cross member resting on and spanning the said pins and having a portion thereof through which one of the pins passes providing a hinged connection between the cross member and the pin.

35 5. A supporting assembly for the roof supports of a mine or the like comprising a pair of separate pins, a cross member resting on and spanning the said pins and having means at one end thereof for embracing one of said pins and providing a pivoting connection between said pin and cross member, said cross member having spaced upstanding lugs thereon between which an end portion of a mine roof support may fit.

45 6. A supporting assembly for the roof supports of a mine or the like comprising a pair of separate pins, a cross member resting on and spanning the said pins and having means at one end thereof for embracing one of said pins and providing a pivoting connection between said pin and cross member, said cross member having upstanding lugs thereon between which an end portion of a mine roof support may fit, both of said pins having enlarged heads on the outer ends thereof.

55 7. A supporting assembly for the roof supports of mines and the like comprising a pair of pins adapted to be driven into the face of a mine wall and to project therefrom, and a strap having an eye portion through which one of the pins passes, the other end portion of the strap resting on top of the other pin, said strap serving as a support for one end portion of a roof support.
